US00D955371S

(12) **United States Design Patent** (10) Patent No.: **US D955,371 S**
(45) Date of Patent: ** Jun. 21, 2022

(54) **MOBILE PHONE**

(71) Applicant: **HUAWEI TECHNOLOGIES CO., LTD.**, Shenzhen (CN)

(72) Inventors: **Joon Suh Kim**, Shanghai (CN); **Ting Xu**, Shanghai (CN); **Zhenqi Tang**, Shanghai (CN); **Lu Huang**, Paris (FR)

(73) Assignee: **HUAWEI TECHNOLOGIES CO., LTD.**, Shenzhen (CN)

(**) Term: **15 Years**

(21) Appl. No.: **29/696,330**

(22) Filed: **Jun. 27, 2019**

Related U.S. Application Data

(63) Continuation of application No. 29/592,863, filed on Feb. 3, 2017, now Pat. No. Des. 853,980.

(30) **Foreign Application Priority Data**

Aug. 5, 2016 (CN) 201630370544.7

(51) LOC (13) Cl. **14-03**

(52) U.S. Cl.

USPC **D14/248**

(58) **Field of Classification Search**

USPC .... D14/138 AA, 138 AB, 138 AC, 138 AD, D14/138 C, 138 R, 138 G, 248, 341, 126, D14/217, 137; D10/65

Primary Examiner — Tracey J Bell

(57) **CLAIM**

The ornamental design for a mobile phone, as shown and described.

DESCRIPTION

FIG. 1 is a front perspective view of a mobile phone, showing our new design;

FIG. 2 is a front view of the design thereof;

FIG. 3 is a back view of the design thereof;

FIG. 4 is a left view of the design thereof;

FIG. 5 is a right view of the design thereof;

FIG. 6 is a top view of the design thereof; and,

FIG. 7 is a bottom view of the design thereof.

The broken lines depict portions of the mobile phone that form no part of the claimed design and form no part thereof.

1 Claim, 7 Drawing Sheets
